HOT AIR REGISTER.

No. 351,230.

Patented Oct. 19, 1886.

UNITED STATES PATENT OFFICE.

JOHN WARREN, OF BOSTON, ASSIGNOR TO HERBERT BARROWS, TRUSTEE,
OF READING, MASSACHUSETTS.

HOT-AIR REGISTER.

SPECIFICATION forming part of Letters Patent No. 351,230, dated October 19, 1886.

Application filed April 28, 1886. Serial No. 200,394. (No model.)

To all whom it may concern:

Be it known that I, JOHN WARREN, of Boston, in the county of Suffolk and State of Massachusetts, have invented a new and useful Improvement in Hot-Air Registers, of which the following, taken in connection with the accompanying drawings, is a specification.

The object of my invention is the construction of a register having a movable face-plate hinged to the frame above, and adapted to swing outwardly and be secured in this outward position, thus forming a rest for the feet or a support for articles which it may be desired to expose to a current of hot air.

15 In the accompanying drawings, Figure 1 is a front elevation. Fig. 2 is a cross-section on line xx of Fig. 1. Fig. 3 is a side elevation. Fig. 4 is a vertical section on a line, yy , of Fig. 1; and Fig. 5 is an under side view of the 20 latch and part of the movable plate B.

The movable plate B, as shown in Figs. 1 and 4 of the drawings, is hinged at its upper end to the top of the stationary frame A, and has its edges grooved to fit the inner edge of 25 said stationary frame A, and has a projecting shelf, c, as shown in Fig. 5, and a hinged latch with a projecting hook, g, as shown in Fig. 5. Said latch has also one or more grooved arms, b, as shown in Fig. 5, which mesh with teeth 30 d in said stationary frame A, as shown in Fig. 4, and thereby retain said movable plate B in position at any desired angle. Said movable plate B has also side wings, C, as shown in 35 Figs. 3 and 4, which extend back from said plate so as to form an extension side when said plate is withdrawn from said stationary frame A. Said wings have curved bases and gradually diminish in width from said bases to the top of said plate.

40 In connection with said hot-air register I make as a part of my invention a device for opening and closing the dampers thereof, consisting of a knob, D, in slot E, as shown in Fig. 1, forming a part of sliding rack f, which 45 meshes with one or more segments of gear e, as shown in Fig. 2, attached to one end of said dampers. Said sliding rack is kept in position

on the one side by said knob running in slot, and on the other side by widening the sides thereof in the intervals between the teeth, so 50 that it is in contact with one or more permanent guides, h, attached to said stationary frame A, as shown in Fig. 2, and it is prevented by stud l, as shown in Fig. 2, from moving beyond a certain point to one side. 55

In using this invention the operator presses down the projecting hook g, and releases the latch and pulls out the movable plate B, which will remain fixed at any incline desired by means of appliances heretofore described. The 60 degree of heat may be regulated by moving the knob D in slot E, as before described.

What I claim is—

1. In a hot-air register, the combination, with the toothed frame A, of the face-plate B, 65 provided with notched arms b, for the purposes and substantially as shown and described.

2. In a hot-air register, the combination of the frame A, having teeth d, with the movable 70 face-plate B, provided with a latch having the hook g, and one or more notched arms, b, hinged to one end thereof, substantially as set forth.

3. In a hot-air register, the combination of 75 the frame A with a face-plate, B, pivoted at the upper end to said frame, and having side wings, C, for the purposes and substantially as set forth.

4. In a hot-air register, the combination of 80 the frame A with a movable face-plate, B, hinged at its upper end to said frame, and provided with a stationary shelf, c, at the lower end thereof, for the purposes and substantially as set forth.

In testimony whereof I have signed my name to this specification, in the presence of two subscribing witnesses, on this 26th day of April, 85 A. D. 1886.

JOHN WARREN.

Witnesses:

CONRAD RENO,
ROBERT WALLACE.
